TIMING AND SIGNALING DEVICE

Harry Hackett, New York, N. Y.

Application August 27, 1936, Serial No. 98,152

7 Claims. (Cl. 161—23)

This invention relates to mechanism for accurately measuring a predetermined interval of time, and producing an audible signal when a predetermined interval of time has elapsed.

5 Among the objects of the invention are to produce a mechanism having a dial containing finger holes graduated according to the length of time which it is desired to measure, a main spring which serves both as a return for the dial and a 10 source of power for the escapement mechanism, a throwout mechanism designed to disconnect the dial from the clockwork while the device is being set and arranged automatically to connect the dial with the clockwork mechanism 15 while the device is in operation, and the use of a mutilated gear permitting the dial itself to serve in addition as the sound producing member of the instrument.

By combining two or more functions in a 20 single part of the apparatus as, for example, arranging the dial to serve both as a measuring instrument and as a sound producing member, the necessary number of parts has been greatly reduced and extreme simplification of construction 25 has been attained.

In the particular form or embodiment of this invention here disclosed by way of illustration, the invention is disclosed as applied to an instrument for timing various specific operations 30 where an audible sound is desired at the expiration of the predetermined length of time—for instance, in timing the boiling of eggs, the immersion of plates or films in development solutions or their exposure to light, the length of telephone 35 toll calls, and the like. Other uses of the invention will readily suggest themselves.

In the drawings annexed to and forming a part of this specification two alternate forms of device embodying my invention are disclosed. 40 One form, herein called the "pendulum device", is shown in Figs. 1-6, inclusive. A second form, herein called the "flywheel device", is shown in Figs. 7-11, inclusive.

Fig. 1 is a perspective view of a device of the 45 first form, made according to this invention.

Fig. 2 is a front elevation thereof with parts of the front cover plate 27 cut away.

Fig. 3 is a rear elevation thereof with parts of the rear cover plate 45 cut away.

50 Fig. 4 is a vertical section thereof on the line 4, 4 of Fig. 2.

Fig. 5 is a horizontal section on the line 5, 5 of Fig. 2, showing the shaft 31 in normal position.

Fig. 6 is similar to Fig. 5, but showing the shaft 55 31 in displaced position.

Fig. 7 is a front elevation of the second form of device embodying this invention, with parts of the annular cover plate 88 cut away.

Fig. 8 is a vertical section thereof on the line 8, 8 of Fig. 7.

Fig. 9 is a rear view of a part of the device shown in Fig. 8, the rear cover plate 53 being cut away so that the view is substantially on the line 9, 9 of Fig. 8.

Fig. 10 is a horizontal section on the line 10, 10 of Fig. 9, showing shaft 68 in normal position.

Fig. 11 is similar to Fig. 10, but showing the shaft 68 in displaced position.

For convenience this specification sets forth the two forms of device separately, although in many respects the same subject-matter of invention is embodied in both.

Pendulum device (Figs. 1-6)

Upon a suitable base 10 is mounted a vertical plate 11 which serves as a support for the mechanism. Secured to plate 11 is a shaft 12 upon which is rotatably mounted a circular dial member 14 of heavy metal. The peripheral edges of dial member 14 are turned downwardly at 15 to 20 enclose a portion of the mechanism hereinafter described and to strengthen the dial. At the inner edges of peripheral portion 15 are formed a series of outwardly projecting gear teeth 16 extending around the entire circumference of the dial with the exception of a mutilated sector hereinafter mentioned. In the mutilated sector (see Fig. 2) the edge of the peripheral portion 15 is bent inwardly and formed into inwardly projecting teeth 17. The function of teeth 16 is to engage the gear wheel 18; that of teeth 17 is to engage the spring-held clapper 19.

Secured to plate 11 is a pin 20. Secured to dial 14 is a pin 21. A helical spring 22, wound around shaft 12 and secured at its opposite ends to pins 20 and 21, is arranged to resist clockwise rotation of the dial 14 (as seen in Fig. 2). Pins 20 and 21 are arranged to engage each other when the dial is at its normal or starting position, and to serve as a stop for the dial.

Near its periphery the dial 14 is drilled to provide a plurality of openings 23, 23 which serve as finger holes to facilitate the operation of the device. An annular plate 24 is secured by welding or otherwise to the back of the dial and carries insignia registering with the several openings 23, indicating the length of time which the device is adapted to measure.

A post 25 is secured to plate 11, and to this post is secured a clapper 19 by a stiff supporting 55

spring 26. The outer end of clapper 19 is adapted to engage with the inturned teeth 17 of the dial 14, and, as these teeth successively pass over the clapper, to cause the dial to give forth a bell-like sound. For this purpose the dial is made of a suitable relatively strong metal.

A front cover plate 27 is secured to plate 11 by rivets 28 and projects forwardly to enclose the gear mechanism hereinafter described, and also 10 to provide support for a finger stop 29. The arrangement is such that the device is set for measuring a predetermined period of time by moving the desired finger hole around to the finger stop, in the manner of operating a dial 15 telephone.

Pivoted in hole 30 of cover plate 27 is a short stub shaft 31 having a reduced end portion 32 for engagement with said hole 30, and having formed integral therewith a smaller gear 18 and 20 a larger gear 33. The arrangement is such that during the period when the device is measuring the predetermined length of time, gear 18 is in engagement with teeth 16 of the dial, and gear 33 is in engagement with gear 39 of the escapement mechanism hereinafter described.

At its end remote from reduced end portion 32, shaft 31 passes through slot 34 in plate 11 and is provided with a reduced end portion 35 journalled within a spring-pressed link 36. Link 36 is rotatably mounted upon pin 37 (see Fig. 3) which is secured in plate 11, and is in yielding engagement with spring 38. Spring 38 is so arranged as to exert pressure upon link 36 in a direction tending to hold said link, and reduced 35 end portion 35 of the shaft 31, in the position shown in Fig. 5, and to resist displacement thereof to the position shown in Fig. 6.

The arrangement is such that when the dial 14 is moved manually in a clockwise direction (as 40 seen in Fig. 2), tooth 16a comes in contact with gear 18 and displaces said gear and shaft 31 to the right (as seen in Figs. 2, 5 and 6) so as to move gear wheel 33 out of engagement with gear 39 (hereinafter referred to). When dial 14 commences to move in a counter-clockwise direction (as seen in Fig. 2) under the influence of spring 22, teeth 16, in engagement with gear wheel 18, will move shaft 31 to its normal position (as seen in Fig. 5). Spring 38 aids in this movement. 50 This movement brings gear wheel 33 into engagement with gear 39 and permits dial 14 to return to its initial or starting position under control of the escapement mechanism hereinafter described.

55 The escapement mechanism comprises a weighted pendulum 40 secured upon shaft 41. Also secured upon this shaft is an anchor displacement mechanism 42 having pallets 43, 43 engaging with the teeth of an escape wheel 44 secured upon shaft 45 journalled in plate 11 and carrying, at one end, gear 39.

A back cover plate 46 having a slot 47 through which the pendulum extends, protects the escapement mechanism and provides a bearing for the 65 shafts 41 and 45.

The operation of the device is such that when it is desired to measure an interval of time as, for example, when an egg is placed in boiling water and it is desired to boil it for three and 70 one half minutes, the finger is inserted in that one of holes 23 of dial 14 which registers with the appropriate indicia (e. g., "3½") and the dial is rotated clockwise until the finger engages stop 29.

At the start of this rotation none of teeth 16 are 75 in engagement with gear 18. During the first

part of this clockwise movement (as seen in Fig. 2), the mutilated sector of dial 14 is beneath gear 18 and hence there is no contact between any of the teeth 16 and gear 18. Upon further rotation of dial 14 in a clockwise direction teeth 16, beginning with tooth 16a, engage the teeth of gear 18 and a lateral thrust is imparted thereto displacing gear 18 and shaft 31 on which it is mounted from normal position (as seen in Fig. 5) to displaced position (as seen in Fig. 6). In this 10 manner gear 33 is moved out of engagement with gear 39 of the escapement mechanism, and the dial may be turned the desired extent in a clockwise direction, the gear wheel 33 meanwhile 15 rotating freely.

When dial 14 has been rotated in a clockwise direction (as seen in Fig. 2) until the finger reaches stop 29, the finger is removed and the dial commences to return in a counter-clockwise direction under the influence of spring 22. Engagement of teeth 16 with gear 18 causes gear 18 and shaft 31 on which it is mounted to return from displaced position (as seen in Fig. 6) to normal position (as seen in Fig. 5) whereby gear 33 is brought into engagement with gear 39. 20 By moving the whole device slightly to start the pendulum swinging, the escapement mechanism commences operation, power therefor being provided from spring 22 through teeth 16 and gears 18, 33 and 39. Accordingly dial 14 rotates in a 25 counter-clockwise direction (as seen in Fig. 2) under control of the escapement mechanism until it approaches its initial or starting position. The speed being constant, the length of time which this return consumes will be directly proportional 30 to the extent of the original clockwise rotation of the dial. When tooth 16a, at the beginning of the mutilated sector, disengages from gear 18, dial 14 moves more rapidly under the impulse of 35 spring 22 until it reaches its initial or starting position at which pin 21 engages pin 20. During this latter period of movement, inwardly turned teeth 17 engage the end of clapper 19 and successively ride thereover. The impact of clapper 19 upon the successive teeth 17 causes bell-like 40 vibrations to be set up in the dial 14 and an audible signal is thus given indicating that the 45 predetermined length of time has elapsed.

Flywheel device (Figs. 7-11)

A plate 50, bent at an acute angle, serves as the base and supporting frame for the second form of device here shown. A shaft 51 is rotatably mounted in plate 50 and a reduced end portion 52 thereof is journalled within a back cover plate 53. Secured upon that end portion of shaft 51 which projects forwardly of plate 50, as by splining or otherwise, are two discs, one a dial 54 of heavy metal and the other a disc 55 bearing indicia, both secured upon the said shaft by nut 56 and separated from each other by spacer 57. Dial 54 is provided with a series of finger holes 58 registering with appropriate indicia upon the disc 55. Dial 54 is provided 60 around all of its circumference, except a mutilated portion hereinafter described, with gear teeth 59. Within a short sector (see Fig. 7) the peripheral edge of dial 54 is turned inwardly at 65 60 and is provided with inwardly disposed teeth 61, arranged to engage a spring-held clapper 62. Said clapper 62 is spring mounted and is secured at 61 to plate 50.

A coiled spring 63 surrounds shaft 51 and is secured at one of its ends to rivet 64 secured to 75

plate 50 and at its other end to pin 65 secured to shaft 51. A pin 66 secured to back cover plate 53 is positioned in the path of movement of pin 65 and serves as a stop to determine the initial or normal position of the dial 54.

Gear wheel 67 is secured upon one end of stub shaft 68. Shaft 68 passes through slot 69 in plate 50 and its opposite reduced end 70 is journalled in back plate 53. Shaft 68 is journalled 10 within link 71 which is pivotally mounted upon a post 72 secured to plate 50. A spring 73 bears upon link 71 and tends to retain shaft 68 in the lefthand end of slot 69 (as seen in Fig. 9).

Upon shaft 68 is secured gear wheel 74 adapted, 15 when shaft 68 is in normal position (as shown in Fig. 10) to engage gear wheel 75 associated with the escapement mechanism. The arrangement is such that movement of dial 54 in a clockwise direction (as seen in Fig. 7) causes teeth 20 59 to engage with gear 67 and to displace gear 67, and shaft 68 on which it is mounted, from the normal position (seen in Fig. 10) to displaced position (seen in Fig. 11), thereby permitting dial 54 to rotate without being in control of the 25 escapement mechanism. Upon return of dial 54 in a counter-clockwise direction (as seen in Fig. 7) under the influence of spring 63, teeth 59 urge gear 67 and shaft 68 from the displaced 30 position to normal position and thus bring gear 74 into engagement with gear 75, thus establishing connection between the dial and the escapement mechanism.

The escapement mechanism comprises a shaft 76 journalled at its ends in plate 50 and back 35 cover plate 53 and having secured thereon gear 76 and escape wheel 77. An anchor escape mechanism comprising anchor element 78 having pallets 79, 79 and balance staff 80 is pivoted on shaft 81 journalled at its opposite ends in plate 40 50 and back plate 53. The forked end 82 of balance staff 80 engages pin 83 eccentrically mounted upon flywheel 84 which is secured upon shaft 85 journalled in bearings at each of its 45 opposite ends in plate 50 and back plate 53. A coiled spring 86 secured to the back plate 53 at 87 and to the shaft 85 permits oscillatory movement of the flywheel 84 in the usual manner.

Around the outer edge of the dial 54 is positioned 50 an annular cover plate 88 secured by screws 89 to plate 50 and serving to conceal the teeth 59 and the gear wheel 67. The annular cover plate 88 carries a finger stop 90 suitably positioned.

This second form of device is similar in its 55 operation to the first. When it is desired to measure an interval of time, the finger is inserted in one of the finger holes 58 according to the interval of time which it is desired to measure. The dial 54 is moved in a clockwise direction until the finger encounters the finger stop 90. In this movement spring 63 is put under tension and it tends to return the dial to its starting position when released from finger 60 pressure.

As dial 54 and disk 55 are both mounted to rotate with shaft 51, both rotate together. During the first few degrees of the arc of rotation of dial 54, the mutilated portion of its periphery is 65 opposite gear 67 (see Fig. 7). When tooth 59a engages gear 67, gear 67 and shaft 68 on which it is mounted are displaced laterally from normal position (as seen in Fig. 10) to displaced position (as seen in Fig. 11). During further rotation of dial 54 shaft 68 turns freely, since gear 70

wheel 74 has by its displacement been disengaged from gear wheel 75.

When dial 54 commences to rotate in a counter-clockwise direction (as seen in Fig. 7) under the influence of spring 63, engagement of teeth 59 with gear wheel 67 moves shaft 68 from its displaced position back to its normal position such that gear 74 engages gear 75. Thereupon further counter-clockwise rotation of dial 54, under the influence of spring 63, is controlled by 10 the escapement mechanism operating through gear train 75, 74, 67 and teeth 59 so long as any of teeth 59 are in engagement with gear 67.

When dial 54 has returned in a counter-clockwise direction far enough so that tooth 59a disengages from gear wheel 67, disc 55 moves more rapidly toward its original or starting position (indicated in Fig. 7). During this period of movement teeth 61 on the inwardly turned portion 20 of dial 54 successively engage the pointed tip of clapper 62. The successive impacts of clapper 62 on these teeth 61 produce vibration of the dial 54 which sets up an audible bell-like tone or warning sound. When pin 66 engages 25 pin 65, the dial has returned to its normal position.

The particular form or type of escapement mechanism which may be used forms no part of this invention, and any suitable type thereof may be employed. In rotating the dial a predetermined extent, as established by selecting the desired finger hole, a predetermined number of the gear teeth around the periphery of the dial are moved so as to pass successively into engagement on the return rotation with the pinion (e. g., 30 pinion 18 of Fig. 2). As this pinion, when shaft 31 is in normal position, is under control of the escapement mechanism and accordingly rotates at constant speed, the length of time which will be measured until the signal is given will be 40 determined by the number of teeth which successively engage this pinion until the last tooth 16a is released thereby.

The dial should be of stiff vibratile material suitable to the production of an audible signal 45 when vibrated. For this purpose steel of fairly heavy gauge is well suited, but the exact thickness or material thereof will depend upon the purpose or use to which the instrument is adapted.

I claim:

1. In timing mechanism, in combination, an indicating dial of vibratile material, means supporting said dial for movement from a position of rest to a predetermined position and return therefrom to its position of rest, resilient means 50 opposing said first movement and furnishing power for said return movement, an escapement mechanism controlling said dial during the major portion of its return movement, a resiliently-held clapper, and a series of teeth formed integral 55 with said dial and adapted as said dial nears the end of its return movement successively to engage said clapper whereby said dial is vibrated to produce an audible signal.

2. In timing mechanism, in combination, an 60 indicating dial of vibratile material, means supporting said dial for rotation from a position of rest through a predetermined arc of rotation and return through said arc to its position of rest, resilient means opposing said first-men- 70 tioned rotation and furnishing power for said return rotation, an escapement mechanism controlling said dial during the major portion of its return rotation, a resiliently-held clapper, and a series of teeth formed integral with said dial 75

and arranged along the arc of a circle concentric with its pivotal center and adapted as said dial nears the end of its return rotation successively to engage said clapper whereby said dial is vibrated to produce an audible signal.

5. 3. In timing mechanism, in combination, a dial of vibratile material having finger holes showing time-measuring indicia, a pivotal mounting therefor, a finger stop mounted in spaced relation to the finger holes in said dial and adapted to limit rotation thereof to a predetermined extent, a pinion, an escapement mechanism associated with said pinion, a set of teeth arranged and adapted to engage said pinion after predetermined rotation of said dial in one direction, and a second set of teeth formed integral with said dial and adapted during a part of the rotation thereof to strike against means secured to a stationary part of the mechanism whereby said dial is vibrated to produce an audible signal.

10. 4. In timing mechanism, in combination, a dial having finger holes showing time-measuring indicia, a pivotal mounting therefor, a finger stop mounted in spaced relation to the finger holes in said dial and adapted to limit rotation thereof to a predetermined extent, a pinion, an escapement mechanism associated with said pinion, a set of teeth arranged and adapted to engage said pinion after predetermined rotation of said dial in one direction, and a second set of teeth formed integral with said dial and adapted during a part of the rotation thereof to strike against means secured to a stationary part of the mechanism whereby an audible signal is produced.

15. 5. In timing mechanism, in combination, pivoted means for selecting a predetermined interval of time to be measured, a pinion, a series of teeth adapted to move with said pivoted means and to engage said pinion, escape mechanism associated with said pinion, means intermediate said pinion and said escape mechanism for disconnecting said pinion and said escape mechanism upon movement of said teeth in one direction

and for establishing mechanical connection between said pinion and said escape mechanism upon movement of said teeth in the other direction, resiliently-held means, and a second series of teeth adapted to move with said pivoted means and during a part of their said movement successively to engage said resiliently-held means whereby an audible signal is produced.

20. 6. In timing and signaling mechanism, a pivoted dial of vibratile material having finger holes showing indicia, a finger stop to limit rotation thereof from initial position to a predetermined position, gear teeth formed around the periphery of said dial and having a mutilated sector, gear teeth within said mutilated sector positioned on a circle different from the circle of said first mentioned teeth, escapement mechanism interconnected through a train of gears adapted to engage with said first-mentioned gear teeth, and a resiliently-held clapper adapted to engage with the teeth within said mutilated sector to vibrate said dial and thereby to produce an audible signal.

25. 7. In timing and signaling mechanism, a pivoted dial of vibratile material having finger holes showing indicia, a finger stop to limit rotation thereof from initial position to a predetermined position, gear teeth formed around the periphery of said dial and having a mutilated sector, gear teeth within said mutilated sector positioned on a circle different from the circle of said first mentioned teeth, a pinion adapted to engage said first-mentioned teeth, a shaft on which said pinion is mounted, an escapement mechanism, gear means interconnecting said pinion and said escapement mechanism, means permitting lateral displacement of said shaft to disengage said gear means on rotation of said dial from its initial to its predetermined position, and a resiliently-held clapper adapted to engage with the teeth within said mutilated sector to vibrate said dial and thereby to produce an audible signal.

HARRY HACKETT.
